Primary Examiner — Darlington Ly(74) *Attorney, Agent, or Firm* — Connie R. Masters(57) **CLAIM**

The ornamental design for a vacuum gripper, as shown and described.

DESCRIPTION

FIG. 1 is a perspective view of a vacuum gripper embodying our new design;

FIG. 2 is a bottom plan view thereof;

FIG. 3 is a left side elevation view thereof;

FIG. 4 is a top plan view thereof;

FIG. 5 is a rear elevation view thereof;

FIG. 6 is a front elevation view thereof; and,

FIG. 7 is a top plan view thereof.

The broken lines in the drawings illustrate portions of the vacuum gripper that form no part of the claimed design.
